UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

RIBBON GUIDE FOR TYPEWRITING MACHINES.

1,417,909.

Specification of Letters Patent. Patented May 30, 1922.

Original application filed January 13, 1921, Serial No. 436,924. Divided and this application filed May 27, 1921. Serial No. 473,171.

To all whom it may concern:

Be it known that we, EDWARD BERNARD HESS and LEWIS CARY MYERS, both citizens of the United States, residing in Brooklyn, 5 county of Kings, city and State of New York, have invented certain new and useful Improvements in Ribbon Guides for Type-writing Machines, of which the following is a specification.

10 This application is a division of our application for patent filed January 13, 1921, No. 436,924.

15 The invention herein claimed relates to ribbon guides for visible front strike type-writing machines, in which the ribbon is passed from spool to spool through a guide which supports the ribbon as it passes the printing point. The invention particularly relates to that class of ribbon guides known 20 as "vibrators" which are reciprocated vertically in order to distribute the wear on the ribbon.

25 According to this invention, the guide is given a novel shape by means of which the ribbon is prevented from twisting, curling, lapping, or becoming otherwise distorted, and the invention also comprises improved means for guiding the ribbon from the spools to the guide or vibrator.

30 In the accompanying drawings:—

Figure 1 is a view in front elevation of the preferred form of ribbon guide or vibrator, and shows how the ribbon is directed from the ribbon spools to the vibrator.

35 Figure 2 is a plan view of the devices shown in Figure 1.

40 Figure 3 is a view on an enlarged scale and in section on the line 3—3 of Figure 1 of mechanism shown in Figures 1 and 2, and illustrates in section some features of this mechanism.

Figure 4 is a view in section on the line 4—4 of Figure 3.

45 Figure 5 is a front view of the preferred form of ribbon guide or vibrator.

Figure 6 is a perspective view of a modified form of vibrator.

50 The ribbon A is conveyed from the spools B and the guides C, D to the ribbon guide or vibrator G which is preferably operated to reciprocate vertically in order that the wear on the ribbon may be distributed. The ribbon guide, or vibrator as it is generally called, and will be hereinafter generally so

called, is preferably of the kind shown in 55 Figures 1-5, inclusive, and it is supported by a type bar guide F, which latter is secured to the type bar segment E. This type bar guide has a base portion f attached to the segment and a front portion f' which extends from the base forwardly and then upwardly in front of the platen and at the top is formed with a bifurcated type guide portion f².

The vibrator G has an upper guide part 65 and a downwardly extending leg G' which is bent and extended rearwardly and then downwardly as shown in Figure 3 where it is connected with an operating lever H actuated in any suitable way. The vibrator G 70 is formed with lips g which engage the type bar guide in such manner that the vibrator is properly held and guided as it reciprocates or vibrates. The upper part of the vibrator is obliquely arranged relatively to 75 the platen X and it is bifurcated as indicated at g' to receive the type and allow them to act on the ribbon. On the opposite sides of the bifurcation, ribbon guiding openings or slots h, h' are formed, the inner parts i of 80 the guide being straight and flat. The upper parts or fingers k, k' are parallel and in the same plane with the parts i, but the lower parts or fingers l, l' are in vertical planes outside the planes of the fingers 85 k, k' and are inclined forwardly and upwardly and their extreme upper ends are turned backward and are rounded. There are spaces m between the fingers for insertion of the ribbon and the fingers l, l' are 90 in a vertical plane outside of or in front of the vertical plane of the fingers k, and k', and laterally to one side thereof. The effect of this construction is illustrated in Figures 1-5, inclusive. The ribbon as it goes from 95 the guide post C, for instance, passes across the upper curved end of the finger l and then through the opening h, across the inner wall of this opening, and in contact with the rear sides of the middle portions i of the guide, 100 and then across the edge of the inner wall of the opening h', next through said opening and around and in front of the upper curved edge of the finger l'.

As will be observed by reference to Fig. 105 3, the ribbon A rises as it leaves the guide post C and as it approaches the vibrator. Without some special provision in the vibra-

tor for preventing it, the ribbon would twist, curve, lap or otherwise become distorted, but by the special construction above described this twisting or distorting of the ribbon is prevented. The finger l makes contact with that portion of the ribbon where it tends to twist and holds it in a flat condition as it enters the vibrator. The behavior of the ribbon and its 10 guide is the same on opposite sides of the device whichever way the ribbon is moving. Unless the lower front fingers be extended forwardly as shown, the ribbon when changing from an upwardly inclined direction 15 to a straight transverse direction would bend near the vibrator and turn the lower part of the ribbon rearward. The fingers l , l' prevent the lower portion of the ribbon from being thus turned backward and correct this tendency and causes it to be directed through the vibrator in a straight, even path. As the ribbon passes through 20 the vibrator it makes contact with the outer walls of the openings h , h' which are in advance of or in a plane in front of the inner walls of these openings, and thus the tendency of the ribbon to twist, lap, or curl is corrected. The high points at the upper ends 25 of the fingers l , l' over which the ribbon passes serve to keep the ribbon taut as well as flat against the flat back face of the vibrator, thus insuring a clear printing impression 30 of the type and preventing interference with some of the working parts which might occur if the ribbon were permitted to buckle 35 behind the vibrator.

It will be observed that the inner edges of the lower fingers l , l' are further distant 40 from the inner walls of the openings h , h' than the inner edges of the upper fingers, the fingers l , l' being in different vertical planes. This also contributes to the proper 45 guiding of the ribbon.

It is not essential that the lower fingers 50 should be in vertical planes to the side of the upper fingers, as the device also operates efficiently when the lower fingers are in the same vertical planes, transverse to the axis of the platen, but the upper or outer 55 ends of the lower fingers should be disposed in front of the upper fingers.

Figure 6 shows another form of vibrator. In this case both the upper and lower 60 guide fingers are in the same plane with each other, but are all set at an angle to the oblique plane of the body of the vibrator. In this case, the ribbon from the guide post C passes over or in front of the upper and lower guide fingers n , n' , then through the 65 opening o behind the middle parts r , then through the opening q , and then in front of the fingers r' , s . This construction also serves in a measure to properly change the direction of the ribbon from an upwardly inclined to a straight across path and to

correct the tendency of the ribbon to twist or buckle, but the construction shown in Figures 1-5, inclusive, is preferred, as experience has demonstrated that such latter construction operates more efficiently. In 70 the construction shown in Figure 6, the fingers are held in the forwardly inclined position by means of webs t .

In order to prevent the ribbon from moving upwards on the posts of the ribbon 75 spool, said posts are formed with heads d which are tapered or coned on their under sides. These posts are preferably mounted to revolve, and are, therefore, in effect ribbon guiding rollers. The ribbon spools B 80 may be operated in any suitable way. The posts b and c of these spools are supported in brackets V, W, as shown in Figure 1. The post b may be geared as shown at b' with a worm shaft D' which is adapted 85 also to engage a toothed wheel c' on a shaft C' which is geared as shown at c'' with the ribbon spool post c . The mechanism for operating the spools is more fully shown and described in our application for patent 90 above mentioned.

The vibrators shown in the drawings are so constructed as to properly guide the ribbon and prevent it from twisting or buckling when operating on either the upper or 95 lower portion thereof. The ribbon is made to pass through the vibrator smoothly and evenly and to be properly wound on the ribbon spools.

We claim as our invention:

100

1. A vibrator for typewriting machines having a body portion, ribbon-guiding portions for the upper portion of the ribbon, and separate ribbon-guiding portions for the lower portion of the ribbon arranged in 105 transverse vertical planes outside the upper ribbon-guiding portions and extending forwardly therefrom.

2. A vibrator for typewriting machines having a body portion, ribbon guiding fingers extending forwardly and upwardly from the lower portion thereof and engaging the lower part of the ribbon in front of the body portion, and separate fingers lying in the plane of the body portion and engaging 115 the upper portion of the ribbon.

3. A vibrator for typewriting machines comprising a bifurcated body portion, ribbon-guiding fingers extending from the upper portion of the body portion, and ribbon-guiding fingers extending forwardly from the lower portion of the vibrator and arranged in planes outside the plane of the upper ribbon-guiding portions.

4. A vibrator for typewriting machines 125 comprising a bifurcated body portion formed with ribbon-receiving openings on opposite sides of the body portion having straight, parallel inner walls, ribbon guiding fingers at the upper part of the vibrator ar- 130

ranged in the same plane with the body portion, and ribbon-guiding fingers for the lower portion of the ribbon extending forwardly from the body of the vibrator and 5 arranged outside the vertical planes of the upper fingers.

5. A vibrator for typewriting machines having a body portion, ribbon-guiding fingers extending forwardly and upwardly 10 from the lower portion of the body and engaging the ribbon in front of the body portion of the vibrator and separate fingers lying in the plane of the body portion and engaging the upper portion of the ribbon, in 15 combination with ribbon-spools arranged below the line of print, and guides for the ribbon also arranged below the line of print.

6. A vibrator having a body portion with a middle opening to receive the type, side 20 portions having openings through which the ribbon extends from the front, the outer wall of each of said openings being further from

the inner wall thereof at the lower part of said opening than at the upper part thereof, and said side portions having side openings 25 through which the ribbon is threaded.

7. A vibrator for typewriting machines having a body portion, upper ribbon-guiding fingers for the upper portion of the ribbon, and lower ribbon-guiding fingers for the 30 lower portion of the ribbon lying forward and outside of the upper fingers, all of said parts being integral.

8. A vibrator for typewriting machines having a body portion, upper ribbon-guiding 35 fingers for the upper portion of the ribbon, and lower ribbon-guiding fingers for the lower portion of the ribbon lying forward and outside of the upper fingers.

In testimony whereof, we have hereunto 40 subscribed our names.

EDWARD BERNARD HESS.
LEWIS CARY MYERS.
